UNITED STATES PATENT OFFICE.

JOSEPH PRENN, OF BOSTON, MASSACHUSETTS.

MECHANICAL BONE-CONDUCTIVE EAR.

1,346,721.

Specification of Letters Patent. Patented July 13, 1920.

Application filed April 11, 1919. Serial No. 289,191.

To all whom it may concern:

Be it known that I, JOSEPH PRENN, a citizen of the United States, and resident of Roxbury, Boston, county of Suffolk, Commonwealth of Massachusetts, have invented a Mechanical Bone-Conductive Ear, of which the following description, in connection with the accompanying drawings, is a specification, like characters on the drawings representing like parts in each of the several views.

This invention relates to apparatus adapted to provide means whereby persons whose normal sound conducting apparatus is defective either partially or wholly, may hear by means of the transmission of sound vibrations through bone conduction directly to the auditory nerves. The apparatus of the invention is specially adapted for use in cases where hearing has been impaired or lost through ailments such as middle ear catarrh, chronic adhesive type of catarrh, chronic closure of the Eustachian tube, otosclerosis, stapes ankylosis, collapses of the cartilaginous meatus, exostosis of the bony canal and other cases where the sound waves cannot be transferred to the auditory nerves through the usual channel of air conduction and the ear drum. The invention is shown as embodied in a mechanical device but it may also be employed with an electrical equipment if desired. A principal object of the invention is to provide an auditory bone conducting device that is equipped and arranged to amplify the sound vibrations as transmitted to a mouth piece, and to impart them to a surface of the cranium adapted for conducting the vibrations directly to the auditory nerves. The foregoing and other objects and advantages of the invention will more fully appear from the following detailed description, and the distinctive features of novelty will be pointed out in the appended claims.

45 Referring to the drawings:

Figure 1 is a side elevation showing a device embodying the invention;

Fig. 2 is a lengthwise central section thereof;

50 Fig. 3 is a transverse section on line 3—3 of Fig. 2; and

Fig. 4 is an end view of the device.

The housing of the device consists in a short thimble body 10 in one end of which 55 is threaded a mouth piece 11, this mouth piece being shown as formed with an inner

peripheral flange 11^a externally threaded to engage an internal thread at the end of the body 10. The body 10 is formed adjacent this internal thread with an annular shoulder 60 or ledge 12, this ledge being adapted to serve as a rest against which a thin vibratory diaphragm 13 may be fitted. This diaphragm is thus held loosely against the ledge 12 by screwing up the mouth piece 11 to the required extent leaving a slight play for the vibration of the diaphragm, the diaphragm being shown as engaged at this peripheral edge by washers of paper or felt 65 interposed at each side thereof. Secured 70 to the thimble body 10 at one side thereof as seen at 15 is a spiral leaf spring 16 which fills most of the body and carries at its center a stylus pin 17. The stylus pin 17 has a button head 18 which may be of rubber 75 or other suitable material adjacent the center of the diaphragm 13 and adapted to be impinged thereby as the diaphragm vibrates to transmit such vibrations to the spring 17, which is free and adapted to receive and 80 transmit such vibrations, being held only at its outer end by the screw secured to the body at 15. At the inner end of the body 10 is secured as by threading the same therein a disk cap 19 having a central opening 85 20 therethrough. A plate 21 shown as transversely bowed outward is preferably mounted to extend across the central part of this opening, this plate being held to vibrate between light springs 21^a mounted in a suitable 90 housing 21^b provided therefor in the cap 19. The plate 21 is shown as having fixed thereto a thin disk 21^c which may be of mica or the like and extending straight across between the ends of the plate 21 in 95 position to be impinged by the point of the stylus 17 to receive vibrations therefrom. Thus the vibrations of the diaphragm 13 are transmitted through the stylus 17 and thence as described through the disk 21^c to 100 the bowed plate 21 fixed thereto which extends across the opening 20 in position to transmit the vibrations to the bony surface against which the cap 19 may be pressed. In use the vibrations of the air from a person talking into the mouth piece 11 or other sound gathered thereby are transmitted to the diaphragm 13 and set up vibrations 105 therein which by the impingement thereof against the button 18 are transmitted to the spring 16 and stylus pin 17 and localized by the special construction and mounting of

said spring and the stylus pin therein. The action of this pin on the plate 21 transmits the vibrations thereto, it being understood that in use the face of the disk plate 19 will be pressed upon the bony surface of the cranium preferably just in front or back of the ear and adapted to receive and transmit the vibrations to the auditory nerves. The body 10 is preferably formed with one or 10 more holes 22 therein maintaining communication of the inside thereof with the outside atmosphere even when the surface of the plate 19 is pressed against the skin of the body closing the opening 20. I am aware 15 that the invention may be embodied in other specific forms without departing from the spirit or essential attributes thereof, and I therefore desire the present embodiment to be considered in all respects as illustrative 20 and not restrictive, reference being had to the appended claims rather than to the foregoing description to indicate the scope of the invention.

Having described my invention, what I 25 claim as new and desire to secure by Letters Patent is:

1. A device of the kind described, comprising a housing body having a mouth piece at one end thereof, a vibratory diaphragm 30 associated with said mouth piece, and a stylus pin adapted to be impinged by said diaphragm, the other end of said body equipped with means energized by said stylus and adapted to be applied to a bone conductive 35 surface of the cranium.

2. A device of the kind described, comprising a housing body having a mouth piece

at one end thereof, a vibratory diaphragm associated with said mouth piece, and a spiral spring fixed at its outer end to said body, and having mounted for vibration therewith at its center a stylus with a button at one end thereof adapted to be impinged by said diaphragm, the pointed end of said stylus equipped with means to coöperate 45 therewith to transmit vibrations to a bony surface of the cranium for the purpose stated.

3. A device of the kind described, comprising a housing body having a mouth piece 50 at one end thereof, a vibratory diaphragm associated with said mouth piece, a spiral spring fixed at one end of said body and having a stylus carried by its other free end adapted to be impinged by said diaphragm, 55 and a means mounted for vibration having an element in position to be impinged by said stylus and adapted to transmit vibrations to a bony surface of the cranium for the purpose stated.

4. A device of the kind described, comprising a housing body having a mouth piece at one end thereof, a vibratory diaphragm adjacent to and in front of said mouth piece, and means mounted and engaged for energization by said diaphragm having an exposed portion of relatively restricted area 65 adapted to transmit localized vibration received by said diaphragm from sound waves of the air to a bony surface of the cranium. 70

In testimony whereof, I have signed my name to this specification.

JOSEPH PRENN.
